EXERCISE DEVICE

Richard L. Chapman, 233 Prospect Ave.,
Waterloo, Iowa 50703

Filed May 29, 1969, Ser. No. 17,406

Term of patent 14 years

Int. Cl. D21—03

U.S. Cl. D34—5

FIG. 1 is a perspective view of an exercise device showing my new design;
FIG. 2 is a right end elevation view;
FIG. 3 is a top plan view;
FIG. 4 is a side elevation view;
FIG. 5 is a bottom plan view; and
FIG. 6 is a left end elevation view.

I claim:

The ornamental design for an exercise device, substantially as shown.
